UNITED STATES PATENT OFFICE.

SOLON O. RICHARDSON, JR., OF TOLEDO, OHIO, ASSIGNOR TO THE W. L.
LIBBEY & SON COMPANY, OF SAME PLACE.

DESIGN FOR THE ORNAMENTATION OF PITCHERS, &c.

SPECIFICATION forming part of Design No. 19,165, dated June 18, 1889.

Application filed April 6, 1889. Serial No. 306,268. Term of patent 3½ years.

To all whom it may concern:

Be it known that I, SOLON O. RICHARDSON, Jr., a citizen of the United States, residing at Toledo, in the county of Lucas and State of Ohio, have invented a certain new and original Design for the Surface Ornamentation of Pitchers and similar Articles of Glassware; and I do hereby declare that the following is a full, clear, and exact description of the invention, which will enable others skilled in the art to which it appertains to make and use the same, reference being had to the accompanying drawing, and to the letters of reference marked thereon, which form part of this specification.

The class to which this design relates is that of ornamentation of glassware, and the design pertains to the ornamentation of the exterior surface of pitchers and similar glass articles.

In the drawing I have shown my design as applied to a pitcher; but it is obvious that it may also be applied to other similar glass articles.

The leading features of my design are a series of panels rectangular in cross-section, with alternate panels of like contour having a figure formed upon the face-surface thereof.

My design consists of a series of beveled panels A, arranged upon the pitcher or other similar article in vertical and circumferential rows, each panel A alternating with a like panel B, ornamented with a many-pointed star C, having an inscribed rosette formed of radial prisms D, by which the prisms and bevels of the squares scintillate and refract the rays of light, giving a pleasing ornamentation to the dish.

What I claim is—

A design for the surface ornamentation of pitchers or similar articles of glassware herein shown and described, consisting in vertical and circumferential rows of beveled panels, each alternate panel having upon the surface a many-pointed star and inscribed rosette formed of prisms, substantially as shown.

In testimony that I claim the foregoing as my own I hereby affix my signature in presence of two witnesses.

SOLON O. RICHARDSON, JR.
